UNITED STATES PATENT OFFICE.

AUGUST KRAUSE, OF BOSTON, MASSACHUSETTS.

FEEDER FOR PRINTING-PRESSES.

No. 921,260.

Specification of Letters Patent.

Patented May 11, 1909.

Application filed March 9, 1908. Serial No. 419,838.

To all whom it may concern:

Be it known that I, AUGUST KRAUSE, of Boston, in the county of Suffolk and State of Massachusetts, have invented certain new and useful Improvements in Feeders for Printing-Presses; and I hereby declare that the following is a full, clear, and exact description of the same, reference being had to the accompanying drawings, forming part of this specification.

This invention relates to improvements in means for feeding forward sheets of paper to be printed.

One object of the invention is to so construct a sheet feeding device for printing presses that a sheet placed upon said feeding device may be positively and accurately fed to the feed rolls.

Another object of the invention is to so construct a feeding device of this nature that the same may be adjusted for sheets of different widths.

Another object of the invention is to improve the feeding mechanism whereby its retractive movement is positively limited.

The invention consists in such peculiar features of construction and combination of parts as shall hereinafter be more fully described and pointed out in the claims.

Figure 1, represents a plan view of the improved feeding apparatus shown in relation to parts of a printing press. Fig. 2, represents an end view of the same. Fig. 3, represents a bottom plan view of portions of the same. Fig. 4, represents a sectional view of parts of the same taken on line 4—4. Fig. 1. Fig. 5, represents an enlarged sectional view on line 4—4 Fig. 1 of parts of the mechanism to illustrate the means for clamping the feeding arms to their slidable rods.

Similar characters of reference designate corresponding parts throughout.

As shown in the drawings in its preferred form the improved feed apparatus is shown in relation to the frame 10 of any usual construction which is furnished with the members 11, 12, 13, and 14 and 15, in the latter of which the shafts of the usual feed rolls 16 and 17 are rotatably mounted.

In bearings of the frame members as 11 is journaled the cam shaft 18 adapted to be rotated in any usual manner and having the cam 19. On the frame member 10 is pivotally mounted the lever 20 furnished at one side of its pivot with the retraction spring 21 which is also secured to a fixed part of the

machine whereby the action of said spring tends to hold the stud 22 of said lever 20 in contact with the cam 19.

To the member 13 is hinged the feed plate 23 supported at its free end on the frame members as 14 and having the parallel slots 24—24 beneath which are the bars 25—25 slidably supported by stirrups 26—26 which depend from the plate 23 and, at their upper ends said bars have perforations in which are engaged the arms 27—27 of the bell cranks 28—28 which cranks are pivotally mounted on studs extending from the under side of the plate 23. At the upper edge portion of the under side of the plate 23 are mounted the studs 29—29 on which is slidably mounted the bar 30 by means of its slots 31—31, the length of which slots limits the movement of said bar to actuate the bell cranks 28—28 with which said bar 30 is engaged. The actuation of this bar is effected, under the swinging of the lever 20 by its cam 19, by means of bell crank lever 32 pivotally mounted at the under side of the plate 23 and pivotally connected with the bar 30; one arm of this lever being positioned to be actuated by the lever 20 and being furnished with the spring 33 which is connected with the stud 34 fixed on said plate 23 whereby, under action of said spring 33 the lever 32 may be swung to so slide the bar 30 and thus actuate the bell crank levers 28—28 to move the slide bars 25 simultaneously toward the bar 30 until their upper ends bear against said bar 3 which holds said upper ends of the bars 25 in practically exact alinement.

Mounted on the slide bars 25 are the clamps 34—34 having the presser blocks 35 and the squared shoulders 36 furnished with screw threaded perforations adapted to receive the screws 37 whereby the clamps 34 are secured to the slide bars 25 and the sheet supports 38, having square openings adapted to fit the shoulders 36, are secured to said clamps. The sheet supports have screw threaded perforations as 39—39 in which the studs 40—40 are secured, these studs being shown as secured in such perforations at the upper ends of the sheet supports but said studs may, when desired, be removed therefrom and may be similarly secured in such perforations near the lower ends of said sheet supports.

In the operation of the machine the shaft 18 is continuously operated, by any well known means and the lever 20 is intermit-

- tently vibrated by the action of the cam 19 on the stud 20 to swing the upper end of said lever toward the rolls 16 and 17 and said lever is retracted by the spring 21. By reason of the forward movement of the upper end of the lever 20 the bell crank 32 is caused to swing on its pivot against the action of its spring 33 and the bar 30 is caused to move lengthwise on its guide studs 29-29 this effecting the swinging of the bell cranks 27-28 and 27-28 and the sliding of the rods 25-25 with their clamps 34 and the sheet supports 38 having the studs 40. If a sheet as a be placed in position on the supports 38 said sheet is positively engaged by the studs 40 and is positively and accurately fed forward to and between the rolls 16 and 17 or their equivalents. On the retractive movement of the apparatus the ends of the rods 25-25 are interrupted by the edge of the bar 30 which forms a gage accurately positioning said rods 25 and the sheet engaging mechanism carried thereby so that all of the studs 40-40 are in alinement at the commencement of each forward movement and as these studs 40 are moved forward simultaneously a certain distance the sheet placed in position must be fed forward accurately.
- 30 The feeding device may be adjusted for feeding forward narrow sheets by the adjustment of the clamps 34 on the rods 25 or by removing the screw studs 40 from the screw threaded perforations at the upper ends of the sheet supports to the similar perforations 39-39 thereof.
- By the hinging of the plate 23 said plate may be swung upward for the examination and adjustment of the mechanism located
- at the under side thereof or beneath the same.
- Having thus described my invention I claim as new and desire to secure by Letters Patent:
1. In a sheet feeder for printing presses the combination with a plate having a series of parallel slots, and a series of rods slidably mounted beneath said plate in line with said slots, of a bar slidably mounted at right angles to the movement of said rods, connections between the said bar and said rods for actuating the rods when the bar is reciprocated, said bar forming an alining abutment for all of said rods, as described.
  2. In a sheet feeder for printing presses the combination with a plate having a series of parallel slots, guides at the under side of said plate in line with said slots, rods slidably in said guides, clamps adjustably mounted on said rods and extending through said slots, flat sheet supports extending in line with said slots and secured to said clamps, and sheet engaging studs removably mounted on said sheet supports, of a bar slidably mounted at the under side of the said plate at right angles to said rods, bell crank levers pivotally mounted on said plate and engaging said bar, and respectively engaging said rods, a spring retracted bell crank pivotally mounted on said plate and connected with said slideable bar, and means for intermittently actuating said bell crank, as described

AUGUST KRAUSE.
